UNITED STATES PATENT OFFICE.

JASPER STANLEY WINGET, OF YORK, AND AUGUSTIN CONVERSE WINGET, OF TYRONE,
PENNSYLVANIA.

CIGAR-WRAPPING MACHINE.

Application filed December 18, 1923. Serial No. 681,367.

To all whom it may concern:

Be it known that we, JASPER STANLEY WINGET, of York, in the county of York and State of Pennsylvania, and AUGUSTIN CONVERSE WINGET, of Tyrone, in the county of Blair and State of Pennsylvania, citizens of the United States, have invented new and useful Improvements in Cigar-Wrapping Machines, of which the following is a specification, reference being had herein to the accompanying drawings.

This invention relates to improvements in cigar wrapping machines, and more particularly to an automatic machine of this character wherein there is provided an effective construction for very rapidly wrapping finished cigars with either tin foil or tissue paper.

One of the joint inventors of the present automatic machine has previously designed and constructed a cigar wrapping machine which works, so far as the operation upon the cigar after it has reached the wrapping bed of the machine, in a somewhat similar manner to the present invention. Application for patent was made upon the first mentioned machine July 7, 1920 and bears Serial No. 394,464 now Patent Number 1,487,649. This machine however is not completely automatic and the present invention in addition to being completely automatic has many improvements embodied in it over the previous machine and those improvements together with their improved results will be described and pointed out in the following specification and accompanying drawings.

The primary object of our invention is to provide an efficient construction of wrapping machine for wrapping finished cigars with either tin foil or tissue paper or such other paper as may be desired.

Another object of our invention is to provide an automatic machine for rapidly and efficiently wrapping finished cigars with tin foil or tissue paper, or the like.

Another object of our invention is to provide an automatic machine for wrapping

cigars in tin foil, tissue paper or the like, in which both the finished cigar and the material in which it is wrapped is delivered automatically to the wrapping mechanism and the cigar is automatically carried forward in the machine and delivered wrapped into a suitable receptacle or the like.

Another object of our invention is to provide an automatic machine for wrapping finished cigars in tin foil, tissue paper or the like which automatically irons, crimps and compresses the wrapping material and cuts off the surplus material at either end of the cigar.

Many other specific objects and notable improvements of construction and improved results of our machine will appear in the following description and accompanying drawings.

Summarizing our machine in general descriptive terms it may be characterized as one in which a belt receives the tin foil or tissue paper wrapper and cigar, and a combined oscillating or reciprocating roller and wrapper ironing, crimping, compressing and cutting-off mechanism is used to effect the desired result. In general this part of the machine is similar to the previously mentioned machine, upon which application for patent has been previously made. In addition to the above mechanism and construction there is combined an automatic means for delivering the cigar and its wrapper to the belt, both mechanisms being driven by suitable power means to constitute as a whole a completely automatic machine from the time the cigar is placed in the feed hopper until the cigar is delivered into a suitable receptacle in its finished wrapped condition.

In the drawings:

Figure 1 is a view in side elevation of a machine embodying our invention.

Figure 2 is an end view of the machine.

Figure 3 is a view in side elevation of our machine, the view being taken from the opposite side from that shown in Figure 1, the feed hopper being shown in section.

Figure 4 is an enlarged fragmentary vertical sectional view of the machine showing the paper and cigar feeding mechanisms and the rolling belt together with the oscillating or reciprocating ironing, crimping, compressing and cutting-off mechanism.

Figure 5 is a fragmentary view in side elevation showing the cigar depositor and its operating mechanism, the cigar being shown deposited upon the belt and the tin foil about to be delivered to the belt preparatory to the wrapping operation.

Figure 6 is a fragmentary vertical sectional view of the feed hopper and feed roll.

Figure 7 is a detailed vertical sectional view showing the adjusting mechanism of the bed plate guides.

Figure 8 is a top view of the cigar depositor.

Figure 9 is a detailed perspective view of the lower jaw of the cigar depositor.

Figure 10 is a top plan view of the machine the view being taken at a point below the feed hopper and roller and the wrapper delivering mechanism.

Figure 11 is a detailed plan view of the wrapper-cutting mechanism.

Figure 12 is a detailed vertical sectional view of the wrapper-cutting mechanism.

Figure 13 is a plan view of the horizontal knife of the wrapper-cutting mechanism.

Figure 14 is a vertical sectional view of the machine, the wrapper-cutting mechanism being shown in full lines.

Figure 15 is a plan view showing the operation of the ironing, crimping, compressing and cutting-off mechanism at stages from the time the cigar is deposited upon the belt until it is delivered in its wrapped condition.

Figure 16 is a fragmentary detailed view in side elevation of a modified form of the machine, particularly for use upon tissue-paper.

Our invention embodies a driving mechanism A, a bed or roller plate B, a wrapping belt C, a wrapper feed mechanism D, a wrapper cutting mechanism E, a feed hopper F, a feed hopper roller G, the cigar depositing mechanism H, the wrapper receiving and depositing mechanism I and an oscillating or reciprocating ironing, crimping, compressing and cutting-off mechanism J, all of which is supported upon the machine frame K.

Machine frame.

The machine frame may be in any suitable form but in the embodiment shown in the drawings it consists of the four legs 1 upon the upper end of which is carried the hollow rectangular frame or base 2. Intermediate the height of the frame there are suitable horizontal braces 3 and below these

braces there is supported a shelf or supplemental base 4 upon which is supported and carried the driving mechanism A. Below the shelf 4 there are shown suitable flanges 5 upon the legs 1 of the frame for receiving a sliding drawer or the like if desired.

Bed or roller plate and belt.

The bed or roller plate as clearly appears in Figures 5, 7 and 10 of the drawings is approximately rectangular in shape and is supported upon the base 2 by suitable legs 6 terminating in the feet 7 which are bolted in place as at 8. The legs 6 extend upwardly and the bed B as a whole is curved as clearly appears in the drawings, more particularly Figure 5. The bed comprises the end 9 over which the cigar first rolls, the bed being cut out beyond this point as at 10 leaving a central solid curved portion or

main roller bed 11 which extends towards the opposite end of the machine. Positioned beneath the main roller bed portion 11 and journaled in the side walls 12 of the bed are two shafts or transversely extending rods 13 which support the two frames 14 upon the top edge of which are mounted the guides 15. These guides have their top edges tapered inwardly towards the main roller bed portion 11 as clearly appears in

Figure 7 of the drawings and carry the inwardly tapered pads or felts 16.

Passing through the two frames 14 is a threaded bolt 17 the center portion of the bolt being formed into a suitable roughened head 18 by which the bolt can be rotated. The opposite ends 19 and 20 of the bolt 17 are provided with male and female threads so that when the bolt is rotated the distance between the two frames 14 can be adjusted.

This adjustment of course is provided primarily for allowing the adjustment of the guide pads 16 in respect to the main roller bed portion 11. This horizontal adjustment makes it possible to use the machine upon cigars of different lengths as the ends of

the cigar being operated upon roll upon the pad guides 16 as the cigar passes over the bed portion 11. The bed plate guides 15 are attached to the frame 14 through the medium of suitable bolts 21 and nuts 22 whereby there is provided a vertical adjustment of the guides if it is desired. To facilitate the rotation of the bolt 17 one end of the bolt is provided with a slot 23 for the reception of a screw driver or the like.

The roller belt C has its one end 24 clamped in place by a cross bar 25 which abuts the outer end of the main roller bed portion 11 while the opposite end of the belt is wound around and suitably fastened to a horizontal shaft 26 which is supported in suitable arms 27, mounted upon the base 2 as clearly appears in Figure 5 of the draw-

ings. This shaft 26 is provided at one end with a head 28 and its opposite end with a ratchet 29. Between the head 28 and the supporting member 27 there is mounted a spring 30. The ratchet 29 is intended to engage a suitable stop and inasmuch as there is a surplus length of belt wound around the shaft 26 the belt can be lengthened or shortened at will. As clearly appears in Figure 7 of the drawings the belt C is of a width to extend over the guide pad 16 in the position shown in this figure which position of the guides is such as to receive a cigar of the greatest length manufactured.

Attention is directed to the fact that one end of the guides 15 slide upon and are supported by the horizontal end portion 31 of the bed plate B.

Combined ironing, crimping, compressing and cutting-off mechanism.

The mechanism for ironing, crimping, compressing and cutting-off the cigar wrapper as it is applied which we have designated generally as J, is supported between the two upwardly projecting arms or rods 32, the lower end of which rods are pivotally mounted upon the inner side of the machine as at 33 upon the horizontal braces 3 of the machine frame K. The upper ends 34 of these rods extend above the highest point of the roller bed B. As previously mentioned this roller bed is curved and the curve of this bed is preferably in the arc of a circle drawn from the center of the pivotal shafts 33 upon which the arms 32 are mounted. Extending transverse and rotatably supported between the upper ends 34 of the arms 32 is a rod or shaft 35 which for the exception of its extremities is squared. Suitably attached to the outer ends of the shaft 35 upon the outer sides of the rods 32 are depending arms 36 each of which carry a roller 37.

A pair of horizontal movable supports 38 are carried upon the squared portion of the shaft 35 intermediate its ends and within these supports is mounted a shaft 39 which has its opposite ends 40 and 41 provided with male and female threads. The shaft 39 is provided with a roughened portion 42 by which it may be rotated. Each of the movable supports 38 has a pair of outwardly extending lugs 43 and a shaft 44 supported between the upper ends 34 of the arms 32 passes through these outwardly extending lugs.

We have termed the shaft 44 the grip carrying rod and supported upon this rod between the lugs 43 of each of the movable supports 38 is a pair of gripping and cutting arms 45, one arm being pivoted to the lugs 43 as at 46 and the other arm being pivoted to the lugs at 47.

These gripping and cutting arms are approximately inverted U-shaped and their upper ends are adapted to act as cams against the outer face of the horizontal supports 38 as will be hereinafter described.

Due to the fact that the shaft 39 is provided with male and female threads the supports 38 together with the gripping arms 45 can be adjusted to and away from each other in accordance with the length of the cigar being operated upon by the machine.

Hopper and hopper feed roll.

The hopper F is provided with an open top 48 and slanting end walls 49, and fastened upon the outer sides 50 of the hopper are horizontal strips 51 with downwardly depending flanges 52 adapted for sliding engagement with the top edge 53 of the housing 54 which housing is supported upon the base 2 by suitable legs or supports 55 as at 56. The bottom of the hopper F is closed by a sliding gate 57. With a hopper constructed in this manner it is possible to remove the hopper from the machine and with the bottom gate in a closed position fill the hopper with cigars and replace it upon the supplemental hopper or housing 54. As the machine is designed to operate upon cigars of different lengths it is necessary that the width of the hopper be varied in accordance with the length of the cigar being operated upon. To accomplish this result the hopper F is provided with supplemental internal side walls 58 pivotally supported from the top edge 59 of the hopper as at 60 so that they may swing with the top edge of the hopper as the pivotal point. Extending lengthwise the interior of the hopper and between its outer side walls 50 and the inner side walls 58 are rotatable shafts 61 extending outwardly beyond the end 49 of the hopper and terminating in handles 62. Positioned at a plurality of points along the shafts 61 are outwardly extending arms 63 which are adapted to engage the inner walls 58 of the hopper and push them inwardly as the shafts 61 are rotated through the medium of their handles 62. Through this arrangement the width of the hopper can be adjusted to center cigars of any length above the supplemental hopper or housing 54.

The supplemental housing 54 has inclined ends 64 and 65. The end 65 of this hopper extends to its bottom but its opposite end 64 bulges outwardly as at 66 to form a hollow circular cylinder 67 with an open bottom 68.

Rotatably mounted within the hollow cylinder 67 upon a transverse shaft 69 is a cylinder 70 having centrally located in respect to its length and completely encircling its circumference a plurality of pockets 71.

adapted to receive the cigars as they pass from the main hopper and down the supplemental hopper.

It is necessary that the cigars from the time they are put in the hopper be centered in respect to the roller bed B and the belt C. We have previously explained how the cigars are centered in the main hopper and they are centered in the supplemental hopper by means of the guides or fins 72 which are horizontally adjustable as to distance one from the other by means of the transverse shaft 73 provided at its end with male and female threads 74 and 75 respectively which is journaled at its opposite ends in the side walls of the hopper and is provided at one end with a nut 76 by which rotation is imparted to it.

The shaft 69 upon which the hopper feed roll 70 is mounted is provided at one end which extends beyond and through the hollow cylinder 67, with a ratchet wheel 77 the purpose of which will be later explained.

25. Wrapper feed and cutting-off mechanism.

Supported upon the base 2 by suitable arms 78 or the like provided with a top 79 is a roll 80 the shaft 81 of which rotates in suitable housings 82 positioned at each side of the top 79. Extending rearwardly from the housings 82 are arms 83 provided at intervals with U-shaped bearings 84 for rotatably supporting the shaft 85 of the roller 86 upon which is carried the tin foil or tissue paper 87 with which the cigars are to be wrapped.

The outer end of the shaft 81 of the roller 80 is provided with a ratchet wheel 88 the purpose of which will be later explained.

The roller 80 is preferably provided with a rubber covering 90 for the reason that the cigar wrapping material is led from the roller 86 downwardly beneath the roll 80 and adapted to be gripped by this roller between its outer surface and the shaft or roller 88 mounted within the top 79. The purpose of the rubber covering is to assure that the roller 80 grips the material sufficiently enough to pull it off of its roller or carrier 86 as the roller 80 is rotated.

The roller 80 is driven through its ratchet 88 by the main driving mechanism A, in a manner which will be hereinafter explained. To prevent the roller 80 from rotating too easily and to put it under tension we have provided the roller with a brake or tension strap 89.

The wrapper cutting-off mechanism designated by E is mounted in front of the driven roller 80 upon the top or bed 79. The housings 82, before mentioned, which supports the roller 80 extend forwardly to the front edge 91 of the top 79 and terminate in upwardly extending portions 92 in which are suitably mounted for vertical reciproca-

tion the uprights 93 which are provided with flat sided outer faces 94 upon which are fastened by suitable screws 95 or the like the knife 96. The cutting edge of the knife is designated at 97 and one end of the cutting edge is in a slightly higher plane than the other so that in operation there is a shearing action. The vertical uprights 93 are provided with a head 98 at their upper ends and between this head and the top of the portion 92 of the housing 82 the uprights are provided with encircling coil springs 99 which springs support the knife in an elevated position.

Between the roller 88 which is mounted in the top 79 and the front edge 91 of the top there is a horizontal knife 100 which is adapted to slide upon the top 79 in a horizontal manner. The knife 100 is pivotally fastened to the top 79 as at 800 this pivotal fastening being at a forward corner of the knife adjacent the front edge 91 of the top 79. Adjacent the two rear corners of the knife are two downwardly extending pins 102 which extend through slotted openings 103 in the top 79. The lower end of these pins 102 carry coil springs 104 the front ends of which are suitably fastened as at 101 and 105 respectively to normally hold the cutting edge 106 in its most forward position. The normal position of the knife 100 is shown in Figure 11 in dotted lines and it will be seen that the cutting edge remote to the pivoted end of the plate extends outwardly beyond the vertical plane of the knife 96 while the opposite end of the cutting edge of the knife 100 is slightly behind the cutting edge of the vertical knife 96. This is due to the fact that one end of the cutting edge of the knife 106 is in a different plane from the other end of the knife or in other words the cutting edge is tapered to give a shearing effect in operation.

Mounted upon the rear side of the knife 96 and at its end which is adjacent the pivoted end of the knife 100 is a wedge 107 which plays an important part in the operation of the cutting mechanism. As the vertical knife 106 is carried downwardly, in a manner which will be hereinafter described, the lower end of the wedge 107 strikes the cutting edge 106 of the knife 100 and moves the horizontal knife backwardly in a horizontal plane, the knife blade 100 moving in a horizontal plane upon its pivotal point 105. The wedge carries the horizontal knife back just sufficiently far so that as the vertical and horizontal knives reach a meeting point they are in engagement and their cutting action is a shearing one. It will of course be readily understood that the paper 87 leads forwardly between the rollers 80 and 88 and passes above the horizontal knife 100 and outwardly between the cutting edges of the horizontal and vertical knives. It

will also naturally follow that as the vertical knife moves downwardly the paper is cut between the two knives.

Wrapper receiving and depositing mechanism.

This mechanism is designated generally by the numeral I and receives the wrapping material as it is cut off by the knife and deposits it upon the belt C.

This mechanism comprises in detail a U-shaped frame comprising two legs 108 and a top or bed 109. The lower ends of the legs are pivoted to the supporting arms 78 as at 110 and this U-shaped frame works against the spring tension of the coil springs 111. Suitably mounted upon the rear edge of the top 109 of this mechanism are up-standing ears 112 which pivotally support as at 113 the arms 114 which carry between them the cross-bar or gripper jaw 115. Through the medium of a coil spring 116 or the like the gripper jaw is normally held down upon the base or what in reality is the lower jaw 109.

As this entire mechanism is moved in its arc upon its pivotal supports 110 in a manner which will be hereinafter described it assumes the two positions shown in full and dotted lines in Figure 5.

When the device is in the position adjacent the cutting knives of the wrapper cutting-off mechanism, as shown in dotted lines of Figure 5 and in full lines of Figure 16, the trigger 117 which is carried by the jaw 115 and extends downwardly through and backwardly beneath the bed or lower jaw 109 strikes the outwardly extending arm 118 which is pivotally supported as at 119 upon the lower end of the vertical upright 93 of the wrapper cutting-off mechanism. As the gripper mechanism moves towards the knives the trigger of the gripping jaw strikes the arm 118 which lifts the gripper jaw.

The pivotally mounted jaw operating arm 118 is held in its normal upright position as shown in Figure 14 of the drawings through the medium of a spring 120.

It is at the time when the gripping mechanism is in place against the knives to receive the wrapping material that the knives are operated and cut off a predetermined amount of wrapping material. To accomplish this the vertical knife must descend and as the jaw operating arm 18 is carried by one of the knife uprights or carriers 93 this arm must move with the upright. The arm 118 is against the jaw trigger but as the knife descends this arm rotates downwardly upon its pivot against the tension of the spring 120 and thereby passes the trigger which of course allows the gripping jaw to descend under the power of its spring 116 thereby gripping the wrap-

ping material which has been cut by the knives, and pushed forward by the roller 80.

Cigar depositing mechanism.

This mechanism is designated by H and appears most clearly in Figures 3, 4 and 5 of the drawings although it is shown in some of the other figures. Figures 8 and 9 are detailed views of this mechanism.

The purpose of this mechanism is to receive the cigar after it has passed through the feed hopper and the cigar is deposited upon this mechanism by the feed hopper roller. As the feed hopper roller deposits the cigar upon the mechanism, the mechanism is located below and slightly in back of the feed hopper roller housing.

The position of the cigar depositing mechanism when it receives the cigar from the feed hopper roller is shown in Figure 4 and the position of the mechanism as it deposits the cigar upon the roller belt is shown in Figure 5. Broadly this mechanism comprises what we have termed the cigar receiving arms which are designated by the numeral 121 and the upper cigar clamping jaw 122 and lower cigar clamping jaw 123.

Rotatably mounted between the legs 55 which support the feed hopper is a horizontal shaft 124 upon which is mounted an upwardly extending U-shaped frame comprising the side frame members 125 and the cross frame members 126 and 127. The lower cigar clamping jaw 123 is suitably fastened as at 128 to the upper end of the side frames 125 and has a flat outwardly extending portion 129 upon which the cigar is adapted to rest. The upper cigar clamping jaw 122 is pivotally mounted as at 130 to the upper ends of the side frame 125 so that the two jaws are in separated relation. Suitably fastened to the cross frame 126 which is rotatably mounted is a rearwardly extending operating arm 131 the front end of which has pivotal connection as at 132 with the upper cigar clamping jaw while the opposite end of the arm has connection with a coil spring 133 which spring is connected to the machine and tends to hold the rear end of the operating arm down. Supported upon a suitable standard 134 is a cam 135 which engages the lower end of the rod 136 which has pivotal connection with the operating arm 131 adjacent its rear end at the point 137. The cam is so shaped as clearly appears in Figure 4 of the drawings that it tends through its engagement with the rod 136 to hold the rear end of the operating arm up against the tension of the spring 133. The cam is also so shaped so that any forward movement of the frame carrying the clamping jaws will allow the spring to exert its downward pressure and thereby lower the upper pivotally mounted clamping jaw and a continued forward movement of

170

175

180

the mechanism will again raise the upper clamping jaw.

As will be readily understood the frame carrying the clamping jaws rotates in an arc upon the horizontal shaft 124. The cigar depositing frame or mechanism H is positioned mid-way the ends of the shaft 124 upon which it is mounted and encircling the shaft between its ends and the frame are coil springs 138 which have one end fastened to the legs 55 as at 139 and their other ends fastened to the side frames 125. By this construction it will be seen that when the shaft is rotated to carry the frame and gripper jaws forward it is rotated against the tension of these coil springs which tend at all times to bring and hold the frame back to its normal position which is that shown in Figure 4 of the drawings.

Pivoted supported as at 140 upon suitable arms 141 which are fastened to the supplemental hopper are the cigar receiving arms 121 which have outwardly extending portions 142 beneath the hopper roll 70 while their opposite ends extend rearwardly and are provided with small weights 143 to normally hold the arms upwardly against the stops 144. When the feed hopper roll 70 is rotated in the direction indicated by arrow cigars roll and drop outwardly from the pockets 71 upon the receiving arms and the weight of the cigar is sufficient to overcome the weights 143 of the arms and lower the cigar upon the flattened portion 129 of the lower cigar clamping jaw 123.

The means for imparting motion to this entire mechanism will be later described together with the time at which this motion takes place in respect to the component operating parts of the entire machine.

Attention is directed at this time however to the fact that the roller belt C which extends from one end of the roller bed to the shaft 26 at the other end of the machine is supported between the shaft 26 and the roller bed upon a roller 145 which is carried upon the rotatably mounted shaft 146 which has its ends journaled in the upper ends 34 of the rods or side arms 32 of the crimping and cutting-off mechanism.

It is upon the slack in the belt C between the roller 145 and the shaft 26 that the cigar depositing mechanism deposits the cigar as clearly appears in Figure 5 of the drawings.

Attention is directed to the fact that the cam 135 which appears clearly in Figure 4 of the drawings is of such a shape that it causes the rod 136 to close its cigar depositing mechanism's upper jaw 122 as this mechanism starts downwardly and to further cause the rod 136 to open the clamping jaw 122 and release the cigar at the time the cigar is deposited upon the belt C, as clearly appears in Figure 5 of the drawings.

The driving mechanism as a whole is designated by the numeral A and is located beneath the bed 2 of the machine frame K, being supported upon the shelf or supplemental bed 4 of the supporting frame.

The driving mechanism is preferably driven through the medium of an electric motor 148 and there is provided the usual fuse box 149 from which lead off the electric wires 150 which are attached to a suitable source of electric energy (not shown) as is common.

The shaft 151 of the motor is provided with an extension 152 which carries a worm gear 153. The extension shaft 152 has suitable bearing support in the vertical upright 154 as at 155.

Mounted upon the shaft 156 which has one end rotatably supported as at 157 in the vertical support 154 and its other end rotatably supported as at 158 in the upper end of the vertical support 159, is a gear wheel 160 the teeth 161 of which are in mesh with the worm gear 153. The gear 160 is keyed to the shaft 156. Mounted loosely on the shaft so that it will rotate with it is a large cam 162 which is approximately elliptical in shape and concentrically mounted upon the shaft 156 as clearly appears in Figure 5 of the drawings. Suitably fastened upon one end of the cam 162 is another cam or roller runway 163. Mounted on the shaft 156 between the cam 162 and the hub 164 of the gear wheel 160 is a supplemental cam 165 which is approximately the same shape as the larger cam and is also concentrically mounted upon the shaft 156. The extending ends of the two cams are in opposite directions. The small cam is rigidly fastened to the large cam.

Upon one side the cam 162 is provided with a hub 166 which has formed therein the teeth 167. Extending upwardly from the hub is a pin 168.

Mounted adjacent the small cam 165 is a collar 169 which is fastened to the shaft 156 by a set screw 170 or the like. This collar prevents the cam construction from end play towards the gear 160.

Mounted upon the shaft 156 and adapted to slide horizontally upon the key 171 which locks it against rotation upon the shaft is a collar 172. This collar is provided with teeth 173 which are adapted to engage the teeth 167 of the hub 166. Surrounding the shaft 156 between the collar 172 and the shaft bearing 158 is a suitable coil spring 174 which is adapted to hold the teeth of the collar 173 normally in engagement with the teeth of the hub 166. This construction is in reality a clutch.

Pivoted mounted upon an L-shaped

backwardly extending bracket 175 which is carried by the upright leg 159 as at 176 is an arm 177. The front end 178 of this arm is provided with an extension 179 which is 5 cam-shaped and is adapted to engage the vertical pin 168 of the cam hub 166.

The opposite end 180 of the arm 177 extends rearwardly from the pivotal point of the arm and is engaged on its upper face 10 by a cam 181 which is mounted upon the shaft 182 which is rotatably supported at one end upon the frame leg 1 as at 183 and supported at its other end in a downwardly extending bracket 184 carried by the cross 15 brace 3 of the frame.

The end of the shaft 182 adjacent the frame leg 1 is provided with a crank arm 185 to which is suitably attached what we have termed the clutch lever 186 which extends outwardly and upwardly and terminates at a point above the base 2 of the frame in a handle 187. Extending through the handle is a set screw 188 which is adapted to engage the upper face of the frame 2 25 and control the extent of the downward movement of this clutch handle. The vertical leg of the clutch handle passes through a U-shaped strip 189 which acts as a guide way. Extending outwardly from the bed 3 30 2 into the guide 189 is a pin 190 which is adapted to engage the notch 191 in the clutch handle, when desired, to retain the clutch handle in its depressed or downward position.

4 35 Suitably carried upon the L-shaped bracket 175 is a bracket 192. Suitably attached to this bracket and bearing against it and the outer end 180 of the arm 177 is a coil spring 193 which exerts a continued 40 upward pressure against the outer end of this arm and thereby normally holds the cam shaped end 179 downwardly upon the cam hub 166.

5 45 From the construction just described it will be seen that with the clutch handle in the position shown in Figure 2 that the cam shaped end or finger 167 is normally held down upon the hub 166 and that a complete rotation of the hub 166 will cause the 50 pin 168 to engage the cam finger. As the cam finger is pivotally supported at the point 194 the vertical pin will push this finger towards the flange 195 of the collar 172, thereby pushing the collar 172 horizontally against the tension of the spring 174 and eventually causing the disengagement 55 of the teeth 167 and 173. As soon as these teeth become disengaged the shaft 156 together with the gear wheel 160 will rotate 60 but the cams 163 and 165 will not rotate as they are mounted loosely upon the shaft. The collar 172 which is connected to the shaft 156 is the main driving means of these cams.

65 It will be further seen that by pushing the clutch arm 186 downwardly and fastening it in this position by engaging its notch 191 under the pin 190 that the finger cam 179 will be lifted above the top of the vertical pin 168 and allow a continued and indefinite rotation of the shaft 156 without disengaging the hub or collar 172 from the cam hub 166. A coil spring 196 tends to normally hold the clutch handle up and thereby disengage the cam 181 from engagement with the outer end of the arm 177. 70 75

A large cam 162 is the main driving medium for the oscillating or reciprocating, ironing, crimping, compressing, and cutting-off mechanism J. The arms 32 of this mechanism are provided with a cross bar or brace 197 in the center of which is suitably mounted a roller 198. The connecting rod 199 has a forked end 200 which engages the roller while its opposite end is pivotally 80 connected at 201 to a suitable upright 202. The front edge of this connecting rod is adapted to bear against the cam 162 as clearly appears in Figure 5 of the drawings 85 and a steel insert 203 is provided to receive 90 wear caused by the rotation of the cam against the rod.

95 It will be seen that when power is applied and the cam 162 rotated the mechanism J will be oscillated or reciprocated back and forth upon its pivotal supports. Two rods 204 having their one ends pivotally supported at 205 extend through the ears 206 of the cross arm 197 terminating in a screw threaded end provided with nuts 100 207 in front of which the shafts are encircled by the coil springs 208 provided at each end with washers 209.

105 As the mechanism J is moved forwardly and over the roller plate B the ears 206 of the cross arm will engage the coil spring 208 before the mechanism J has reached the end of its stroke. From the time the ears strike the coil springs until the mechanism reaches the end of its stroke, its forward 110 movement is made against the tension of these coil springs. As the motive power continues to revolve the large cam the highest point of the cam will have pushed the mechanism to the end of its forward stroke 115 and the mechanism will again start back. As the cam is elliptical in shape the forward and back movement of the mechanism J is quite rapid and the backward movement of the mechanism is especially rapid 120 as it is being accelerated by the action of the compressed coil springs 208 before mentioned and the spring 400.

125 The small cam 165 is the driving means for the feed hopper roller G. A roller 209 which is suitably fastened to the end of the crank arm 210 which is in turn rigidly connected to the rotatably mounted shaft 211

engages this cam. The shaft 211 is supported between the two brackets 212 and has a rearwardly extending crank arm 213 to which is adjustably fastened as at 214 the 5 rearwardly and upwardly extending lever 215 the upper end of which is pivotally connected to the forwardly extending crank arm 216 the inner end of which is rigidly connected to a shaft 217 which extends through 10 the vertical leg 55 and has rigidly connected thereto the upwardly extending arm 218 the upper end of which pivotally carries the trigger 219 the end of which is provided with a roller 220 for engaging the teeth of 15 the ratchet wheel 77 of the feed hopper roller. The arm 218 is provided with a set screw 221 for limiting the forward movement of the trigger. The shaft 69 of the feed hopper roller is provided with a supplemental ratchet wheel 222 the teeth of 20 which are engaged by a spring detent 223 to lock the roller against backward rotation, and to prevent too free a rotation.

When the motive power is on and the 25 small cam 165 is being rotated it will be seen that once every complete revolution of this cam the feed hopper roller will be rotated sufficiently to deposit a cigar upon the cigar receiving arms 142.

The supplemental cam 163 carried upon the end of the large cam 162 is the driving means for the cigar depositing mechanism H.

A crank arm 224 which is pivotally mounted as at 225 carries in its lower end a roller 226 which engages the rear face of this cam while the opposite end of the crank arm is pivotally connected at 227 to an upwardly extending rod 228 the upper end of which is pivotally connected at 229 to the outer end of the lever 230 the inner end of which is attached to the shaft 124 upon which the cigar depositing mechanism is mounted.

Through the medium of this supplemental cam or rollerway 163 the cigar depositing mechanism is carried forward to deposit the cigar upon the roller belt C at the proper predetermined times.

The roller 80 which pulls the cigar wrapping from the roller 86 and pushes it forward beneath the knives of the wrapper cutting mechanism E is operated by the vertical arms 32 of the oscillating or reciprocating mechanism J.

One of the vertical arms 32 is provided with an outwardly projecting pin 231 which is adapted to engage the adjustable element 232 carried by the lower end of the upwardly extending operating rod 233 which is pivotally mounted intermediate its length at 234 and has its upper end pivotally connected at 235 with the crank arm 236 which is in operative engagement with the arm 237 which in turn moves the trigger 238 which engages the ratchet teeth of the ratchet

wheel 88 of the roller 80. The spring 239 normally holds the ratchet trigger in engagement with the ratchet wheel teeth while the spring detent 240 prevents backward rotation of the roller.

The amount of rotation imparted to the ratchet wheel can be controlled by the adjustable element 232. When the arm 233 is carried forward to impart rotation to the roller 80 it works against the tension of the 75 coil spring 241 which brings the parts back to their original position after the roller has been rotated. To prevent the coil spring from pulling the vertical crank arm 233 back too far we have provided a stop 242 so for engaging this arm.

Among the most important features of the invention are the camways 243 which are mounted upon the base 2 at either side of the roller plate. These cam or rollerways 85 are curved and mounted adjustably upon them as at 244 are the supplemental camways 245.

The rollers 37 of the reciprocating mechanism J roll upon this camway and it is this 90 camway which controls the time at which the gripping arms 45 will close and cut off the ends of the cigar wrapper. By raising or lowering the supplemental camway 245 the point at which the gripper arms will 95 eventually close is controlled. To assure that the ends of the cigar wrapper are cut off before the cigar leaves the machine we have provided the upwardly extending arms or projections 246 adjacent the edges of the rear end of the roller bed plate. These arms are adjustable vertically and their upper ends are in the path of travel of the gripper arms and will strike the two forward gripping arms and force them towards their 100 coacting gripper arm and definitely assure that the wrapper ends are cut off, it being understood, if it has not been mentioned before, that the opposing edges of the gripper arms are cutting edges.

The rollers 37 of the mechanism J are held down upon the roller camway through the medium of the springs 247.

Pivotedly mounted at 248 are crank arms 249 the ends 250 of which engage the pins 115 251 carried upon the lower end of the vertical knife uprights 93. The opposite ends of these crank arms carry the links 252 upon which are rotatably supported the rollers 253. These rollers are supported slightly 120 above and adjacent the rear end of the cam or rollerways 240 and 244.

As the oscillating or reciprocating mechanism J nears the end of its forward stroke the rollers 253 engage the rollers 37 and ride up over them and fall back in behind them. When the reciprocating mechanism has reached the end of its stroke and starts back its rollers 37 strike the rollers 253 and force them upward thereby forcing the ends 125 130

250 of the crank arms 249 downwardly which in turn pulls the vertical knife supports 93 downward against the compression of the springs 99. As the vertical knife 96 5 is carried upon these vertical arms 93 the vertical knife is forced downwardly past the edge of the horizontal knife, thereby cutting off a strip of wrapping material. It is of course understood that when the vertical 10 knife descends its wedge strikes the horizontal knife plate as it has been previously described.

The width of the strip of wrapping material which is cut off is controlled through 15 the mechanism which rotates the roller 80 and thereby advances the wrapping material between the knife blades.

Attention is directed to the fact that the 20 links 252 which carry the rollers 253 which operate the vertical knife are free to swing forward but after these rollers have dropped in behind the rollers 37 and the reciprocating mechanism J starts back thereby causing the rollers 37 to strike the rollers 253 25 the links cannot swing because they are forced against the stops or shoulders 254 of the crank arms 249. The links being unable to swing the roller 253 rides up over the roller 37 thereby moving the end of the 30 crank arm which is in engagement with the pin 251 downwardly thus bringing the vertical knife across the face of the horizontal knife.

The specific construction of the wrapper 35 receiving and depositing mechanism which is designated generally by the numeral I has been previously described.

Pivottally attached to one of the legs 108 of this U-shaped frame at the point 255 is 40 a crank arm 256 which has its lower end pivottally connected to a bell crank 257 which in turn is pivottally supported from the bracket 258 at 259. In the lower face of the bell crank there is provided a cam shaped slot 260 which is adapted to receive a projecting pin 261 which is carried by and extends outwardly from one of the arms 32 of the mechanism J. As has been described the U-shaped frame works against the tension of the coil spring 111 when the frame 50 is in the position shown in Figure 1 of the drawings. Rubber bumpers 262 which act as stops for the frame are mounted in suitable supports 263 mounted upon the ends 55 of the roller camways 244.

From this it will be seen that when the reciprocating mechanism J moves forwardly the pin 261 through its engagement with the cam slot 260 of the bell crank arm 257 lifts 60 the U-shaped frame upwardly upon its pivotal supporting pins 110 until the U-shaped frame abuts the cutting knives, the U-shaped frame being then in the position shown in dotted lines in Figure 5 of the drawings and in full lines in Figure 16.

When the U-shaped frame is in the position shown in Figures 4 and 5 of the drawings its gripper jaw 115 is retaining the cigar wrapper 264 and about to deposit it in front of the cigar 265 which has been previously placed upon the roller belt C by the cigar depositing mechanism H. 70

As the reciprocating mechanism J moves forward the arm 266 provided with a beveled face 267 which is mounted upon the leg 32 75 of this mechanism strikes the end 268 of the pivotally mounted trigger 269. The opposite end 270 of the trigger is in engagement with a rod 271 which is attached to the gripper jaw 115 of the wrapper depositing mechanism and this rod extends downwardly through the lower jaw 109 of this mechanism. When the arm 266 strikes the lower end of the trigger it naturally lifts the opposite end of the trigger which in turn exerts an upward force upon the rod 271 thereby lifting the upper gripping jaw 115 80 against the tension of its spring which releases the wrapper 264 and allows it to fall by gravity upon the roller belt in front of 85 the cigar in the manner shown in Figure 15 of the drawings. A continued forward movement of this reciprocating mechanism carries the pin 261 out of engagement with the slot in the bell crank 257 and the spring 111 carries the wrapper depositing mechanism on upward to the position where it abuts the knives, the mechanism J continuing forward to the end of its stroke. 90

Meanwhile the arm 266 has ridden past the trigger 269. When the reciprocating mechanism J starts back the pin 261 will again engage the slot in the bell crank 257 and carry the wrapper depositing mechanism 105 downwardly to the position shown in Figure 5 of the drawings, the trigger 269 having ridden over and past the rear end of the arm 266 and again assumed the position shown in Figure 5 of the drawings. 110

Operation.

Let us assume that the feed hopper F has been filled with cigars and the adjustable side walls of the hopper positioned properly to agree with the length of the cigars. The sliding bottom of this hopper is then pulled to an open position which allows the cigars to fall into the supplemental hopper 54 the guideways 72 of which have been properly adjusted to the cigar length so as to center 115 it above the feed hopper roller G. 120

Tin foil or other suitable cigar wrapping material 87 is on the roller 86 and this roller is centered upon its shaft 85 through the medium of the horizontal adjustable members 272. The end of the wrapping material leads downwardly and under the driving roll 80 as clearly appears in Figures 1 and 4 of the drawings. 125

We will further assume that the machine 130

has been in operation and that we find the parts in the positions shown in Figure 4 of the drawings.

It will be seen from this figure that the feed hopper roller is being rotated so as to deposit a cigar upon the cigar receiving arms 121.

We will now start the motor of the machine which will cause the rotation of the worm gear and the large gear 160. As these parts rotate carrying with them the several cams 162, 163 and 165 the first action to take place is that the gripping jaws of the cigar depositing mechanism move forward and clamp the cigar and carry it downward and deposit it upon the roller belt C. The cigar depositing mechanism has a downward movement sufficiently far so that when it deposits the cigar it depresses the slack in the roller belt in the manner shown in Figure 5 of the drawings.

The power still being on the next action to take place is that the cigar depositing mechanism now goes up and assumes its first and original position as shown in Figure 4 of the drawings so as to receive and deposit the next cigar from the feed hopper roller at the proper time.

Attention is directed to the fact that the clutch operating lever is fastened in its depressed position so that the clutch throwing-out mechanism is not in operative position.

It will be seen that the next movement is that of the oscillating or reciprocating, ironing, crimping, compressing or cutting-off mechanism J. This mechanism starts forward. The gripper arm operating rollers 37 of this mechanism are rolling upon the camway 244 while the roller 145 over which the roller belt C passes is assuming a position above the cigar, thus carrying the roller belt over the cigar.

It will be seen that the wrapper receiving and depositing mechanism I is at the bottom of its downward stroke and that its gripper jaws are holding a cigar wrapper 264.

As the oscillating or reciprocating mechanism J continues forward the jaw operating mechanism of the wrapper receiving or depositing mechanism is actuated, thereby depositing the cigar wrapper on the belt in the manner shown in Figure 15 of the drawings.

As the oscillating mechanism continues its forward movement the wrapper depositing mechanism is lifted out of the path of travel and is eventually lifted to the position shown in dotted lines in Figure 5 of the drawings. Meanwhile the oscillating mechanism is continuing its forward stroke and the roller 145 has passed above the cigar and assumed a position in front of it thereby having completely encircled the cigar in the cigar wrapper in the manner shown at

273 in Figure 15 of the drawings. The gripping and cutting-off arms 45 are still in separated position.

As the operation of the machine continues the gripper arms are gradually closed through the medium of the rollers 37 rolling upon the curved camway 244 or 245 as the case may be due to the position in which the supplemental camway 245 is adjusted.

The continued forward movement of the oscillating mechanism brings the gripping arms in contact with the wrapper in the manner shown at 274 and it is from this point onward that the wrapper is ironed, crimped and compressed upon the cigar. These wrapper arms cause a twisting of the ends of the wrapper which extend beyond the ends of the cigar thereby ironing and compressing the wrapper upon the cigar.

As the oscillating or rolling mechanism continues forward the gripper arms gradually tighten upon the wrapper and when the mechanism has reached the position shown at 275 the wrapper has been tightly ironed and compressed upon the cigar, the wrapper ends being tightly twisted into extending points 276.

Just before the gripping and cutting-off arms reach the point 277 the roller 80 is actuated through the mechanism which heretofore has been described and the rotation of this roller is continued until the oscillating or cigar rolling mechanism reaches the end of its stroke.

When the cigar oscillating or rolling mechanism reaches the point 277 the gripping and cutting-off arms have completely closed and if their cutting edges have not already severed the tightly twirled extending ends 276 of the wrapper this operation is assured by the forward gripping arms striking the part 246 and forcing these forward gripping arms backwardly thereby severing these ends of the wrapper.

It will be seen that a continued forward motion of the oscillating or rolling mechanism will deliver the completely wrapped cigar with its wrapper ironed, crimped and tightly compressed at the end of the roller bed into any suitable receptacle or shoot.

It will be seen that as the oscillating or cigar rolling mechanism passes forward from the point where the wrapper ends are severed that the rollers 253 have ridden over the rollers 37 and fallen in behind them as has been previously described.

When the roller 80 was actuated it shoved the wrapping material 87 forward beneath the waiting upraised jaw 115 of the wrapper receiving and depositing mechanism I. As the oscillating or cigar rolling mechanism starts its backward stroke the rollers 253 are lifted upwardly thereby bringing

the vertical knife downwardly and severing the wrapping material.

Attention is directed to the fact that the backward motion of the cigar oscillating or rolling mechanism is very rapid due to the elliptical shape of the cam 162 and also to the fact that the coil springs 208 are driving this mechanism backward. These springs were compressed during the forward motion of the cigar rolling mechanism.

As the cigar rolling mechanism continues its backward motion the pin 261 carried by the mechanism's leg 32 strikes the bell crank 257 and through its cooperating parts carries the wrapper depositing mechanism downward to the position shown in Figure 4 of the drawings. Attention is directed to the fact that the jaw 115 of the cigar depositing mechanism through the action of its spring 116 had clamped the cut-off portion 264 of the wrapping material 87 and carried it along as appears in Figures 4 and 5 of the drawings.

As the oscillating or cigar rolling mechanism approaches the end of its backward stroke the supplemental cam 163 acts upon the crank arm 224 and its associated parts, thereby rotating the feed hopper roller G to cause this roller to deposit a cigar upon the cigar receiving arms 142 as shown in Figure 4 of the drawings.

This constitutes one complete movement of the machine and it will be readily understood that a continued operation would be merely a repetition of the operation which is described, as a cigar is now in a position to be grasped by the cigar depositing mechanism and placed upon the roller belt C to be wrapped in the manner just described.

From the foregoing it will be seen that we have provided a cigar wrapping machine which is automatic in every respect with the exception of keeping the feed hopper filled with cigars. The only attention which an operator need give to the machine is to see that the feed hopper is supplied with cigars, that there is a roller supplied with wrapping material and that the wrapped cigars are taken care of as they are delivered at the forward end of the roller bed plate B.

It has been found that with the proper power mechanism this machine will deliver wrapped cigars at the forward end of the roller bed plate at a very rapid rate. We do not however limit ourselves as to the speed at which the machine will operate as this could no doubt be developed so as to be even greater than the speed mentioned.

We wish however to direct attention to the fact that the cigars are very efficiently wrapped and that the material is ironed and compressed upon the cigars with the ends of the wrapper tightly crimped upon the

ends of the cigar the wrapper ends being severed very close to the cigar ends so as to make a neat finish.

We have described the foregoing construction of machine as operating upon both tin foil and tissue paper wrapping material. We have found in practice that the machine will operate upon both of these materials. We have also discovered that with the machine operating at a high speed that its work upon tissue material is not as efficient as upon tin foil material. For this reason we have designed a modification of certain parts of the machine which are described herein-after under a proper heading.

We have also found that it is sometimes necessary to run through the machine cigars which have previously been packed in boxes without wrappers. In packing these cigars in the boxes they have been compressed and these cigars should be run through the machine, wrapped and replaced in the boxes in the exact positions they originally had so that they will go back into the boxes properly without compressing or bruising the cigars again to make a finished and neatly packed job. The manner in which we accomplished this will be hereinafter described.

Modified form.

As has been previously mentioned we have provided a modification of the invention, which appears in Figure 16 of the drawings, which is particularly adapted for use upon tissue paper wrappers for the cigars.

When tissue wrapping material is used for the cigars we do not usually utilize the wrapping material roller or the wrapper material feeding roller. Consequently these parts together with the arms 83 which form an extension of the standards 82 are removed from the machine. The arms 82 carry upon their forward ends the housings 92 and consequently these housings are also removed from the machine as they form an integral part of the uprights.

We have also found that it is better to have the wrappers cut the proper shape and size for the cigars so we also do away with the vertical knife 96 and its supporting uprights 93. The absence of these parts will be seen upon an examination of Figure 16 of the drawings.

It is however necessary to have the mechanism comprising the pivotally supported arm 118 for operating the trigger 117 of the clamping jaw 115 of the wrapper receiving and depositing mechanism I. The construction of the arm 118 is the same as has been previously described in the preferred form of machine. As the uprights 93 have been removed we substitute in place thereof the upright 500 which is carried in the housing 501 in the end of the horizontal

member 502 which is clamped upon the bed or plate 79 as at 503. As will appear the arm 118 is mounted upon the lower end of the upright 500 and the upright 500 is held in its elevated position through the medium of the coil spring 504.

The operation of the arm 118 upon the trigger of the cigar depositing mechanism is the same as has been previously described.

10 The wrappers for the cigar which have been previously cut the proper size and shape are pushed forward by hand across the top of the horizontal knife 100 until their forward edges abut the front 66 of the roller feed housing 67 and are there supported upon a suitable horizontal ledge 505 provided for the purpose.

15 The wrapper depositing mechanism is operated in the same manner as in the preferred form and deposits the wrapper upon the belt at the proper time as has been described.

20 In place of the roller bed guides 15 we substitute the guides 506 provided with the upper padded edge 507 which is beveled in a like manner to the guides removed from the machine. The guides 506 are adjustable to and away from each other through the medium of the shaft 508 in a like manner 25 to the guides which have been removed.

25 In fact in substituting these guides we substitute in place of the frame 14 the frame 509 upon the upper edge of which are carried the guides 506 which are adjustable vertically through the medium of the nuts and screws 21 and 22.

30 The frame 509 carries at its forward end a plate 510 which slides vertically in the end 511 of the frame. The upper end of the plate 510 is notched as at 512 and the rearwardly extending upper edge of the plate is provided with a knife edge 513. The lower end of the plate 510 is designated at 514.

35 The plate 510 is provided with two elongated slots 515 and 516. Mounted upon the outer face of the plate 510 and adapted for vertical reciprocation is a plate 517 having elongated slots 518 one positioned above the other in a like manner to the slots 515 and 516 of the plate 510. Carried upon the outer face of the plate 517 is a link 519 through the upper end of which passes a bolt 520 which passes through the upper elongated slots 515 and 516 of the two plates and is provided at its inner end with a nut which is clamped against the end portion 511 of the frame 509. A bolt 521 penetrates the lower end of this link and passes through the two lower elongated slots and is provided at its inner end with a bolt clamped against the inner face of the end portion 511.

40 The lower end of the plate 517 is desig-

nated at 522 while its upper end terminates 45 in a knife 523.

Supported upon the inner ends of the bolts 520 and 521 is a downwardly extending arm 524 the lower end of which extends outwardly in a horizontal leg 525 which is 50 in separated relation to the lower ends of the two plates 510 and 517.

55 A coil spring 526 has its one end fastened to the horizontal leg 525 and its other ends fastened to the outer knife plate 517 and 60 tends to draw this plate downwardly. The extent of the upward and downward movements of the two plates is controlled through the bolts 520 and 521 which together with the slots of the two plates form stops as 65 well as guides.

70 Pivotedly mounted upon the frame 509 as at 527 is a forwardly extending crank arm 528 the lower end 529 of which is adapted to engage the lower end 514 of the inner plate. 75 Intermediate the ends of this crank arm is an outwardly extending portion or cam 530. Pivotedly mounted at 531 upon the crank arm 528 is a crank arm 532 which extends forwardly so that its end 533 is adapted to 80 engage the lower end 522 of the outer plate 517. This crank arm carries an L-shaped bracket 534 which is adapted to engage the crank arm 528 and support the shorter crank arm 523 as shown in Figure 16. The shorter 85 crank arm 532 is provided with an extending portion or cam 535 intermediate its length. As also appears in Figure 16 of the drawings the ends 529 and 533 are supported upon the horizontal leg 525. 100

90 Pivotedly mounted as at 536 between the two brackets 537 suitably placed upon the legs 32 of the reciprocating or cigar rolling mechanism J there is a rod 538 the lower extending end 539 of which is provided with 105 a coil spring 540 which normally holds the rod against the stops 541 which are mounted upon the brackets 537.

95 The rod 538 when moving with the reciprocating mechanism J travels in a line to 110 engage the two crank arms 528 and 532.

100 It will be understood that in operation the cigar is placed upon the belt as is also the tissue paper wrapper. As the cigar rolling mechanism J starts its forward stroke 115 the wrapper is rolled upon the cigar in the same manner as has been described in respect to the preferred form of the machine. The gripper arms 45 act upon the ends of the wrapper in the same manner as described in the preferred form so as to iron and compress the wrapper upon the cigar and twirl or twist the wrapper ends beyond the ends of the cigar. When the cigar reaches the point upon the roller belt adjacent where the extending ends 513 of the inner plates 510 are located the rod 538 has 120 engaged the two cams 530 and 535 of the 125

two crank arms 528 and 532 and lifted these crank arms so that the ends of the larger crank arms are abutting the ends of the inner plates and the ends of the smaller crank arms are abutting the ends of the outer plates. As the rolling mechanism J continues to advance carrying with it the rod 538 it will be seen that both the inner and outer knife plates are lifted upwardly so that the notches 512 of the inner knife plates are a little above the roller guides. This upward movement carries the inner knife plates to the top of their stroke but the top of the stroke of the outer plates has not yet been reached. At this moment the cigar has reached a position upon the roller bed so that its twirled extending ends enter the notches 512. A continued advancement of the cigar rolling mechanism J and the rod 538 causes the rod to lift the outer knife plates to the top of their stroke and thereby cause their knife edges 512 to pass the knife edges 513 of the inner knife plates and thus sever the twirled ends of the tissue paper wrapper.

The continued forward movement of the cigar rolling mechanism J delivers the finished wrapped cigar at the end of the roller plate. Meanwhile the rod 538 has passed on beyond any engagement with the crank arms, thus allowing the spring 526 to bring the knife plates back to the positions shown, in Figure 16.

When the cigar rolling mechanism J starts its backward stroke it will be seen that the rod 538 will again engage the crank arms 528 and 532 but due to the pivotal support of the rod it will be forced downwardly against the tension of its coil spring 540 and thereby cause no upward movement of the crank arms or the plates.

Special operation.

We have previously mentioned that where cigars have previously been packed in a box without wrappers it is desirable that these cigars be run through the machine and placed in a box in the same positions they originally had.

To accomplish the proper repacking of the box after the wrappers have been applied to the cigars it is preferable to run the cigars through the machine slowly. Accordingly we preferably remove the hopper F from the machine and deposit one cigar at a time into the supplemental hopper where it finds its way into the cigar receiving grooves of the feed hopper roller G.

We also depress the clutch handle 186 and fasten it in its depressed position so that the machine can only make one complete operation, or in other words wrap one cigar, before the finger cam 178 will function to dis-

connect the driving means for the cams 162 and 165.

The box of packed cigars is dumped upside down into some suitable receiver and starting with the bottom row of cigars they are run through the machine one at a time and as they are delivered wrapped at the forward end of the roller bed they are replaced in the original box in their original positions. It is understood that the cigars are run slowly through the machine by depositing one cigar at a time into the supplemental feed hopper and causing one revolution of the machine to wrap the cigar. However if the operator so desires the operation of the machine can be made continuous and the operator can control the speed at which the cigars go through the machine by the interval of time between the depositing of each cigar in the supplemental feed hopper.

When operating in this manner the cigars being wrapped are usually expensive cigars and may have decorations upon the wrapper which makes it necessary that the wrapper be placed in a specific position upon the belt to cause the decorations to be properly positioned upon the cigar. If this be the case the wrappers will be cut to size and shape and it will be unnecessary to use the vertical cutting knife 96 of the machine or the wrapper feed roller 80, the wrappers being fed to the wrapper depositing mechanism I by hand in a similar manner as described in respect to the modified form described for use upon tissue paper.

We have found that where manufacturers have a large supply of cut wrapping material on hand which is cut the proper size and shape for the cigar, that they desire to use up this supply before ordering material in rolls. If this be the case the automatic wrapper feeding and cutting means is disconnected from the machine as has been described under the heading of "Modified form" and the ready cut material can be fed by hand. When the ready cut material has all been used the automatic cutting and feeding device may be replaced on the machine and the wrapping material ordered in rolls so as to make the machine automatic in every respect.

Roller belt.

We have previously mentioned that it is very important that the roller belt C be absolutely centered in respect to the roller plate.

From time to time it will be necessary because of wear to replace belts. In order to assure that these belts are properly and absolutely centered we have provided belts with eyelet openings which are adapted to

receive and engage suitable studs 600 which are provided in the cross bar 25 and the horizontal belt shaft 26. The new belts are supplied with the eyelet openings properly positioned and as the studs are a permanent part of the machine it will be seen that in placing a belt upon the machine it will be impossible to get it in other than in a properly centered position.

10 Having thus described our invention, what we claim and desire to secure by Letters Patent is:

1. A machine for wrapping cigars or the like, comprising a belt, a reciprocating mechanism carrying gripping means for holding the ends of a wrapper, a wrapper feed mechanism for feeding the wrapping material, a mechanism for cutting the wrapping material, means for depositing the severed wrapper upon the belt, and means for closing the gripping means after the wrapping is completed.

2. A machine for wrapping cigars or the like, comprising a belt, a feed mechanism for feeding the wrapping material, a mechanism for severing the wrappers from the wrapping material, a mechanism for depositing the several wrappers upon the belt, a cigar receiving and feeding mechanism, a mechanism for depositing the cigars upon the belt, a reciprocating mechanism carrying gripping means for holding the ends of a wrapper, and means for closing the gripping means after the wrapping is completed.

3. A machine constructed as described in claim 1, having stationary roller-ways constituting the means for closing the gripping means after the wrapping is completed.

4. A machine constructed as described in claim 2, having stationary roller-ways constituting the means for closing the gripping means after the wrapping is completed.

5. A machine for wrapping cigars or the like, comprising a belt adapted to receive a wrapper, a reciprocating mechanism carrying gripper-means for holding the ends of the wrapper, the gripper-means located at opposite ends of the wrapper, and vertically extending projections in the line of travel of said gripper-means for positively operating them to sever the ends of the wrapper after the wrapping is completed.

6. A machine for wrapping cigars or the like, comprising a belt, means for delivering a wrapper to the belt, means for delivering a cigar upon the deposited wrapper, a reciprocating mechanism carrying gripper-means for holding the opposite ends of the wrapper as the cigar is rolled within the same by the belt, and vertically extending projections in the line of travel of the gripper-means for operating them to sever the ends

of the wrapper after the wrapping is completed.

7. In a machine of the type described, adapted to roll a cigar in a wrapper having extended ends, comprising means for rolling the cigar and wrapper over a bed-plate, a wrapper feed mechanism for feeding the wrapping material, a mechanism for cutting the wrapping material, means for depositing the severed wrapper upon the rolling means, and means travelling with the cigar for twisting the extended ends of the wrapper by the rolling action of the cigar.

8. In a machine of the type described, adapted to roll a cigar in a wrapper having extended ends, comprising means for rolling the cigar and wrapper over a bed-plate, a feed mechanism for feeding the wrapping material, a mechanism for severing the wrappers from the wrapping material, a mechanism for depositing the severed wrappers upon the rolling means, a cigar receiving and feeding mechanism, a mechanism for depositing the cigars upon the rolling means, and means travelling with the cigar for twisting the extended ends of the wrapper by the rolling action of the cigar.

9. A machine of the type described, comprising a bed-plate, a reciprocating frame, a wrapping belt having its ends attached to the bed-plate, a roller carried by the frame and co-acting with the belt and bed-plate for wrapping a sheet around an elongated circular object, grippers carried at opposite sides of the frame for gripping the ends of the sheet, elongated cam-ways at opposite sides of the bed-plate, the cam-ways adapted to close the grippers at a predetermined time, the said parts in combination with a feed mechanism for feeding the wrapping material, a mechanism for severing the wrappers from the wrapping material, a mechanism for depositing the severed wrappers upon a belt, a cigar receiving and feeding mechanism, and a mechanism for depositing the cigars upon the belt.

10. A machine for wrapping cigars or the like, comprising a belt, a reciprocating mechanism carrying gripper means for holding the ends of a wrapper, means for closing the gripper means after the wrapping is completed, and supplemental means for actuating the grippers to sever the ends of the wrapper.

11. A machine of the type described, comprising a belt, a reciprocating wrapping means co-operating with the belt, gripping means holding the ends of a wrapper, adjustable cams for closing the gripping means at a predetermined point, and means for actuating the gripping means to sever the ends of the wrapper.

12. In a machine of the type described, adapted to roll a cigar in a wrapper having extended ends, comprising means for rolling

the cigar and wrapper over a bed-plate, a cigar bin having a feeding mechanism, a mechanism for receiving and depositing a cigar upon the rolling means, said cigar feeding and depositing mechanisms adapted to operate automatically at the end of each complete operation of the cigar rolling

means, and means traveling with the cigar for twisting the extended ends of the wrapper by the rolling action of the cigar.

In testimony whereof, we hereunto affix our signatures.
